METHOD OF MANUFACTURING CONTAINER
CLOSURESJohn J. Williams, Wheeling, W. Va., assignor to
Hazel-Atlas Glass Company, Wheeling, W. Va.,
a corporation of West Virginia

Application September 3, 1936, Serial No. 99,312

2 Claims. (Cl. 113—121)

The invention relates to a method of manufacturing metal closures for containers, particularly closures having an incurled bead below the threads or other container engaging means.

5 The more important objects of the invention are to increase the rate of production of closures of this type, to reduce the cost thereof, and to reduce the number of steps required in the production of a closure of this type.

10 Various other objects and advantages of the invention will be apparent to those skilled in the art, from the following detailed description, when taken in connection with the accompanying drawings, which

15 Figure 1 is a vertical sectional view of the cut and draw die for forming the blank from sheet metal, the die being in elevated position.

Figure 2 is a similar view, but showing the die in lowered position.

20 Figure 3 is a vertical sectional view of a curling die; the die being in elevated position.

Figure 4 is a fragmentary vertical sectional view of the same die, but in lowered position.

25 Figure 5 is a vertical sectional view of the blank as formed by the cut and draw die.

Figure 6 is a vertical sectional view of the blank after an incurled bead has been formed by the curling die; and

30 Figure 7 is a vertical sectional view of a completed cap.

Referring to the drawings in more detail numeral 1 indicates a fixed cutting ring having a cutting edge 2. A movable blanking ring is indicated by numeral 3, and numeral 4 refers 35 to a fixed drawing plug. Mounted for vertical reciprocation is a die, referred to generally by numeral 5, which cuts the blank and shapes it. Numeral 6 refers to a clamping ring which is mounted on the die and is normally urged downward by coil springs 7. When the die descends the clamping ring engages the metal strip 8 from which the blank is to be cut, and the peripheral edge 9 in cooperation with the cutting edge 2 cuts the blank. The apparatus for cutting the 45 blank is old, it does not per se form a part of the present invention, and need not be described in any detail.

The drawing plug 4 has a reduced upper cylindrical portion 10, a shoulder 11, and a larger cylindrical portion 12 below the shoulder. The die has a cylindrical portion 13 to cooperate with the cylindrical portion 12 of the drawing or shaping plug, a shoulder 14 to cooperate with the shoulder 11, and a cylindrical portion 15 to cooperate with the cylindrical portion 10. Thus

after the blank has been cut the continued downward movement of the die causes the blank to be drawn and shaped to the shape of the plug. The blank thus shaped is referred to by numeral 16, and is shown in Figures 2 and 5. This blank 5 has a skirt of two different diameters; the portion of the skirt which is of less diameter is referred to by numeral 17, and it is joined by a shoulder 18 to the portion 19 of the skirt which is of greater diameter.

10 The die 5 may be provided with an ejector pad 20, which is normally held in elevated position with respect to the die, by a coil spring 21 mounted on the pad stem 22. The ejector pad is shown in its elevated position with respect to the 15 die in Figure 2, where the die is in its lowered position, and it will be noted that the pad does not contact with the blank. When the die is elevated the stem 22 eventually strikes a stop (not shown), thereby stopping the upward movement 20 of the pad, and the continued upward movement of the die causes the blank to be ejected.

15 The blank having been shaped to the form shown in Figures 2 and 5, it is ready for the curling operation, which will now be described; reference being had particularly to Figures 3 and 4. Numeral 23 refers to a plug which has its upper end hollowed out to receive the blank 16, as shown in Figure 3; the blank having been inverted from the position in which it was formed. The plug 30 25 is provided with an annular shoulder to support the shoulder 18 of the blank, and the enlarged skirt portion 19 of the blank projects freely upward, ready to be incurled.

20 Numeral 25 refers to a die holder which may 35 be secured to the ram of an ordinary press (not shown) or to any other desired mechanism providing a reciprocating movement. Numeral 26 indicates a guide or centering ring which is attached to the guide holder, and which has a 40 snug fit with the skirt portion 19 of the blank; the lower end of the ring being preferably flared, as indicated by numeral 27.

25 The curling ring or die is referred to by numeral 28. It is mounted in the die holder, and 45 is provided with a continuous annular groove 29, which in the form illustrated is substantially semi-circular in cross-section. Numeral 30 refers to a clamping and ejector pad which may be employed if desired. This pad has an 50 upwardly extending stem 31, and arranged about the upper end of the stem is a coil spring 32; the lower end of the spring being seated in the upper end of the die holder, and the upper end of the spring bearing against a washer 33. With- 55

- in the holder there is arranged about the stem 31 a heavy coil spring 34; the upper end of the spring bearing against the holder, and the lower end thereof bearing against a washer 35.
- 5 As the press descends the guide or centering ring 26 snugly fits around the cylindrical skirt portion 19 of the blank, thereby supporting this skirt portion to prevent any outward bulging of the skirt when the die acts on the edge thereof.
- 10 The clamping pad 30 now engages the base of the blank and firmly holds it in position. The pad now remains stationary but the curling ring or die continues to descend against the pressure of the spring 34. The continued descent of the die 15 brings the annular groove 29 into engagement with the upstanding edge of the enlarged skirt portion 19, and as the die descends farther the metal of the skirt is curled inwardly to form an incurled bead 36, as shown in Figures 4 and 6.
- 20 The die holder now moves upwardly, and during the first part of the upward movement the pad is held stationary against the cap blank, by reason of the spring 34. The cap is thus removed from the die but it remains in the centering ring 26 because of the snug fit. As the upward movement of the holder continues the die ring 28 and washer 35 come together, whereupon the pad rises with the holder. During the continued upward movement the stem 31 of the 25 pad strikes a stop (not shown) on the press. This causes the upward movement of the pad to be stopped while the holder and its associated parts, including the centering ring, continue to rise, the spring 32 being compressed. The blank 30 with the incurled bead is thus ejected from the centering ring. While I have described in detail the specific apparatus disclosed here, it is to be understood that the invention is not limited to any particular apparatus, or to any apparatus 35 for ejecting the blank after the curling of the bead. So far as the step of incurling the bead is concerned, the only apparatus required is the plug to support the blank of this particular shape, a die having a continuous annular groove, and 40 means for reciprocating the die.
- 45 The enlarged cylindrical skirt portion 19 has

now been converted into an incurled bead 36, and it will be noted that this incurled bead projects outwardly of the smaller skirt portion 17, so that when the threads or other container attaching means, are formed in the skirt portion 17 there will be no interference between the threads and the incurled bead. The cap in its present incomplete form is shown in Figure 6 and is referred to by numeral 37.

The blank is now in condition to be placed 10 on an ordinary threader to form any desired container engaging means, such as the threads 38. The cap is thus completed, and is shown in Figure 7, where the finished cap is referred to by numeral 39.

15 It will be apparent that by the method disclosed herein closures with an incurled bead and with threads or other container attaching means can be rapidly and efficiently manufactured, and that the number of steps involved in the manufacture are reduced to a minimum. It will be understood, of course, that the invention is in no manner limited to the particular apparatus shown and described.

20 Having fully described the invention, what I claim is:

1. The method of manufacturing single shell metal closures with an incurled bead, which comprises drawing in a single step a blank with a top and a plain cylindrical skirt portion and an 25 enlarged plain cylindrical skirt portion below the first-mentioned portion, then curling the lower enlarged cylindrical portion into an incurled bead, and forming container engaging means in the upper cylindrical skirt portion.

2. The method of manufacturing single shell metal closures with an incurled bead which comprises drawing in a single step a blank with a top and a plain cylindrical skirt portion and an 30 enlarged plain cylindrical skirt portion below the first-mentioned portion, then curling the lower enlarged cylindrical portion into an incurled bead, and forming container engaging threads in the upper cylindrical portion.

JOHN J. WILLIAMS. 4
